US0D1047340S

(12) **United States Design Patent** (10) Patent No.: **US D1,047,340 S**
Churchvara et al. (45) Date of Patent: ** Oct. 15, 2024

(54) **WHEEL BASE ASSEMBLY**(71) Applicant: **Veltek Associates, Inc.**, Malvern, PA (US)(72) Inventors: **Jeffrey Churchvara**, Downingtown, PA (US); **Arthur L. Vellutato, Jr.**, Malvern, PA (US); **Yefim Gudesblat**, Exton, PA (US); **Vladislav Gudesblat**, Exton, PA (US)(73) Assignee: **VELTEK ASSOCIATES, INC.**, Malvern, PA (US)(***) Term: **15 Years**(21) Appl. No.: **29/789,991**(22) Filed: **Oct. 28, 2021****Related U.S. Application Data**

(60) Division of application No. 29/718,431, filed on Dec. 24, 2019, now Pat. No. Des. 939,178, which is a division of application No. 29/630,655, filed on Dec. 21, 2017, now Pat. No. Des. 871,708, which is a division of application No. 29/569,050, filed on Jun. 23, 2016, now Pat. No. Des. 809,730, which is a continuation-in-part of application No. 14/979,330, filed on Dec. 22, 2015, now Pat. No. 10,518,793.

(57) **CLAIM**

The ornamental design for a wheel base assembly as shown and described.

DESCRIPTION

FIG. 1 is a front perspective view of a wheel base assembly showing our new design;

FIG. 2 is a rear perspective view thereof;

FIG. 3 is a front view thereof;

FIG. 4 is a rear view thereof;

FIG. 5 is a left-side view thereof;

FIG. 6 is a right-side view thereof;

FIG. 7 is a top view thereof; and,

FIG. 8 is a bottom view thereof.

1 Claim, 8 Drawing Sheets
